DISPENSING PUMP

Application filed December 30, 1929. Serial No. 417,308.

This invention relates to a dispensing pump which is adapted to deliver a measured quantity of gasoline or other liquid. In connection with electrically operated pumps, meters as usually constructed are notoriously inaccurate since their operation varies considerably with the voltage of the electric line and also with the liquid pressure and rate of discharge, as controlled by the valve in the nozzle. Self-measuring pumps can seldom be stopped accurately.

It is therefore an object of the present invention to provide a pump which may be accurately controlled even by a novice and which will accurately measure the amount of liquid discharged, regardless of the character of the liquid or the rate of discharge. According to the preferred construction, the complete pump includes two double acting pump units connected to a common pipe line and so timed that when one piston is at the top or bottom of its stroke, the other piston will be midway of its stroke, thus insuring a substantially uniform and continuous flow. Special provision is also made to prevent any accumulation of gas in the system and also to effectively prevent leakage around the piston rod. We have also provided improved means controlled from the nozzle for opening or closing the motor circuit, and this is so arranged that the stopping of the pump at a predetermined point may be effected with the utmost precision.

The above and other important features of our invention will be more specifically pointed out in connection with the accompanying drawings, which illustrate one embodiment thereof.

In the drawings:

Figure 1 is a side elevation of the invention with parts broken away, or shown in section.

Figure 2 is a similar view taken at right angles to Figure 1.

Figure 3 is a vertical section taken on the line 3-3 of Figure 1.

Figure 4 is a section taken on the line 4-4 of Figure 1.

Figure 5 is a plan view of the pump with the casing shown in section.

Figure 6 is a vertical section through the pump cylinders and parts associated therewith.

Figure 7 is a detail sectional view taken on the line 7-7 of Figure 6.

Figure 8 is a section taken on the line 8-8 of Figure 6.

Figure 9 is a section taken on the line 9-9 of Figure 8.

Figure 10 is a wiring diagram of the circuit controlling the motor.

As illustrated in the drawings, the pump is enclosed within a casing 1 and the various parts thereof are supported by a skeleton framework 2 secured to a base 3. The pump has two cylinders 4, each provided with a lower head 5 and an upper head 6, the lower head 5 of both cylinders consisting in the present instance of a single casting. Within each cylinder 4 is a double acting piston 7 secured to the lower end of a piston rod 8 which extends upwardly through the upper head 6.

The lower head 5 of each cylinder is divided into two compartments 9 and 10, the compartment 9 being in direct communication with the lower end of the cylinder and the compartment 10 being connected by a passageway 11 of ample proportions to a chamber 12 within the upper head 6, the chamber 12 being in direct communication with the upper end of the cylinder 4. The lower head 5 has an extension 13 which forms a valve box. The bottom of this box is provided with a cover 14 forming an inlet chamber 15 which is connected by a pipe 16 to the reservoir where the gasoline or other liquid is stored. The upper face of the valve box 13 is provided with a cover 17 forming an outlet chamber 18 which has a discharge pipe 19 leading therefrom. The covers 14 and 17 are connected by a rod 20 provided at its ends with socket nuts 21 which with suitable gaskets insure the valve box against leakage, yet permit easy access to the valves.

As will be readily seen from Figures 6, 7 and 8, the piston 7 upon its upward stroke draws the liquid from the pipe 16 and chamber 15 past the check valve 22 into the chamber 9 and the lower end of the cylinder, and

upon its downward stroke forces the same from the lower end of the chamber 9 past the check valve 23 and into the chamber 18 thence into the discharge pipe 19. The piston upon its downward stroke also draws liquid from the pipe 16 and chamber 15 past the valve 24 into the chamber 10 and passageway 11, chamber 12 and the upper end of the cylinder. Upon the upward stroke this liquid is forced back through the chamber 10 and through a similar check valve into the chamber 18 and thence into the discharge pipe 19. The discharge pipe 19 extends across the casing 1 and thence upwardly as shown at 25 and through the upper part of the casting 1 where it is connected with the hose 26.

For reciprocating the piston 7, the upper end of the rod 8 is connected to the lower end of a pitman 27. The upper end of the pitman 20 is connected to a disc or gear wheel 28 by means of an eccentric wrist pin 29 which may be adjusted to vary the stroke of the piston until each stroke thereof delivers exactly one quart of liquid or any other quantity which corresponds to the capacity of the pump. The connection between the rod 8 and the pitman 27 preferably comprises a yoke 30 secured to the rod 8 and carrying a pin 31 on which is a rotatable disc or wheel 32 adapted to ride up and down in a guideway 33 secured to the frame. The pitman 27 is provided at its lower end with a yoke 34 which straddles the yoke 30 and is journaled on the pin 31. By this means the piston is reciprocated accurately with the least possible friction.

The two wheels 28 which drive the two pistons are secured to shafts 35 journaled in the upper end of the frame and are set in mesh with each other with one wrist pin 90° in advance of the other, so that one piston will always be half a stroke ahead of the other and a substantially uniform and continuous flow will be obtained from the two double acting pistons.

For driving the shafts 35, one of them has a gear wheel 36 secured thereto and driven by a pinion 37 secured to a countershaft 38. On this countershaft is a gear wheel 39 which is adapted to drive the shaft through the medium of a friction clutch connection 40 keyed to the shaft and held in engagement by a spring 41 which may be adjusted to the desired tension by means of a nut 42. The gear 39 is driven by suitable speed reduction gearing 43 from an electric motor 44 which is mounted on a support 45 substantially midway of the frame 2.

For indicating the amount of liquid dispensed, the opposite sides of the casing 1 are provided with dials 46. Associated with each dial is an indicator including a sleeve 47 and a shaft 48 extending through the sleeve. Secured to the inner ends of shafts 48 are beveled pinions 49 which are connected

by a drive pinion 50. The pinion 50 is secured to a shaft 51 rotatably mounted within a sleeve 52 which is secured to a stationary shaft 53. The shaft 53 is supported in brackets 54 having sleeves 55 in which the shafts 35 are rotatable. The sleeve 52 is formed with a yoke 56 in which the inner ends of the shafts 48 are journaled. The shaft 51 is connected to one of the shafts 35 by spur gears 57 of equal diameter and the beveled pinions 49 and 50 are of equal diameter so that each of the shafts 48 will complete one rotation for each rotation of the shafts 35 during which the pump completes one cycle of its operation. A hand connected to the shaft 48 will therefore indicate small fractions of a gallon of liquid dispensed, and in a pump of the usual capacity, a complete revolution of the hand will take place for each gallon. A bell 58 may also be arranged to strike at each revolution of the shaft 35.

Each sleeve 47 is adapted to complete a rotation for each twenty gallons dispensed or for any other number of gallons desired. For this purpose a worm 59 is secured to each shaft 35 and drives a worm gear 60 carried by the sleeve 47. This worm gear, however, is connected to the sleeve 47 through a spring held friction clutch 61 to permit the indicator arm carried by the sleeve 47 to be reset at zero after each sale.

For resetting the indicator arms carried by the sleeves 47 there is provided a shaft 62 journaled in brackets 63 and 64 which are secured to the ends of the fixed shaft 53. One end of the shaft 62 carries a sprocket wheel 65 which is connected by a sprocket chain 66 to a sprocket wheel 67 on one of the sleeves 47. The shaft 62 is rotated for resetting by means of a knob 68 which is connected by means of a ratchet 69, so that the indicator on the other side must be turned in the opposite direction. For this purpose a sprocket wheel 70 secured to the shaft 62 is connected by a sprocket chain 71 to an idler sprocket wheel 72 mounted at the end of the bracket 63. This sprocket chain passes underneath sprocket wheel 73 secured to the sleeve 47. Thus the two sleeves 47 are rotated in opposite directions for resetting the indicator.

In the present instance, the motor 44 is controlled through the medium of an electric circuit having two leads through switches 74 and 75 respectively and a common return wire. Springs are connected to the switches 74 and 75 tending to hold the switch 74 closed and the switch 75 open. These switches are mounted in a box 76 which is pivotally supported at 77. A dog 78 is secured to the box 76 and is limited in its rocking movement about the pivot 77 by a pin and slot 79. When the dog 78 is raised as shown in Figure 3, it is directly in the path of a stop arm 80 secured to the wheel

36, so that the rotation of the latter will cease precisely at the conclusion of the revolution, which is taking place when the dog is raised. A rod 81 is slidably mounted longitudinally 5 of the dog 78 and is normally projected beyond the end of the dog by a spring 82. As the stop bar 80 comes into engagement with the end of the dog, it engages the end of the rod 81, shifting it rearwardly and opening the switch 74. The switch 75 is already held open by its spring, but as soon as the dog 78 is lowered below the path of the stop bar 80, swinging the switch box 76 rearwardly, a pin 83 extending rearwardly from the switch 75 15 engages a fixed stop 84 and closes the switch 75. 75 As soon as the dog 78 is raised again the switch 75 is opened by the switch 74 remains closed until it is again opened through the medium of rod 81. The opening of switch 74 20 opens the circuit to the motor either directly or through the medium of a remote control switch or relay, while the closing of the switch 75 closes the circuit through the motor.

25 In the operation of gasoline pumps, it is desirable, especially because of the fire hazard, to control the operation through the medium of a relay, as indicated by the wiring diagram in Fig. 10. In this arrangement the 30 main circuit L^1, L^2 through the motor M has a switch S adapted to be closed by the magnetic coil c^1 . The switch box 76 has three terminals adapted to be connected to the wires w^1, w^2 and w^3 respectively. The wire w^1 is connected through resistance R to line L^1 . The wire w^2 is connected through coil c^1 , relay switch s, and coil c^2 to line L^2 . The switch 74 is normally closed but this does not close a circuit through coil c^1 unless switch s 35 is closed and switch s will not be closed until switch 75 is closed to establish a circuit from line L^1 through resistance R, wire w^1 , switch 75, wire w^3 , and coil c^2 to line L^2 . This circuit energizes coil c^2 and closes switch s. 40 When both switches 74 and 75 are closed, therefore, a circuit is established from line L^1 through resistance R, wire w^1 , switch 74, wire w^2 , coil c^1 , switch s, and coil c^2 to line L^2 . Then, although the switch 75 is immediately 45 opened again, the circuit through the coil c^1 is maintained until the switch 74 is opened. Thus it will be seen that both switches 74 and 75 must be closed to start the motor but, although switch 75 is immediately opened again, the motor will not stop until switch 74 50 is opened.

For shifting the dog 78, a rod 85 is connected at its upper end to the dog and is connected at its lower end to a piston 86, which 55 operates within a cylinder 87. The lower end of the cylinder 87 is connected through a nipple 88, T 89 and pipes 90 and 91 to the pipe 25, which is connected with the discharge line from the cylinders 4. It is apparent, therefore, that the piston 86 and dog

78 remain in lowered position as long as the liquid is discharging freely from the nozzle of the hose 26. If, however, the nozzle valve is closed or partially closed, pressure is developed in the system which is sufficient to raise the piston 86 and to shift the dog 78 into the path of the stop arm 80, so that the operation of the pump will be positively stopped at the moment that the discharge of the next gallon of liquid is completed. 75

The line to the switch 75 is preferably through a switch 75^a, which is so arranged that it will be opened by the weight of the hose when the latter is hung up but will be automatically closed when the hose is taken off the hook. If the pump stands idle for a considerable length of time, the slightest leak will allow the pressure to escape. This pressure should be restored, before the hose is taken from the hook. For this purpose a small receptacle 92 is provided which should always be at least partially filled with the liquid. The interior of this receptacle is connected with the bottom of the cylinder 87 by a pipe 93 leading to the T 89. The inlet to the pipe is provided with a valve box 94 containing check valves 95 and 96, through which the liquid is pumped by a piston 97 connected by a link 98 to a hand lever 99. Usually one stroke of the lever 99 will be sufficient to restore the pressure to the system. 85

As soon as pressure is restored to the system, the piston 86 will maintain the dog 78 in a stop position. When the nozzle valve is opened to dispense the liquid, the pressure 100 will be immediately lowered, the piston 86 and dog 78 will drop, and the switch 75 will be closed to start the motor. In lowering the piston 86, gravity is assisted by a spring 100 mounted between a fixed bracket 101 and a 105 collar 102 secured to the rod 85.

In pumping or otherwise agitating such volatile liquids as gasoline, more or less gas is liberated from the liquid. In the present construction, the shafts 35 are designed to complete only about fifteen revolutions a minute, so that the deliberation of gas is reduced to a minimum. Nevertheless, it has been deemed advisable to provide means for permitting the escape of any gas or air which 110 may occur in the system. For this purpose, small outlets 103 are provided in the tops of the heads 12 to allow for the escape of the gas which naturally seeks the highest point in the pump. These outlets 103 are 115 connected through check valves 104 and pipes 105 to the pipe 91 which leads to the discharge pipe 25. Thus, while the main discharge of the liquid from the pumps is through the outlet 19, there is ample opportunity for the discharge of any gas which may be formed, along with some liquid, 120 through the outlets 103.

The piston rods 8 extend from the cylinders 4 upwardly through packing glands 106 125

which are held in position by nuts 107. In order to move any liquid which may leak past these glands and to prevent any possible escape of such liquid, each gland 106 is formed with an internal groove 108 from which radial ducts 109 lead outwardly to an annular groove 110 formed in a flange to which the nut 107 is screwed. From the groove 110 a duct 111 leads downwardly and into a pipe 112 discharging into a small receptacle 113, from which a pipe 114 leads to the receptacle 92. A pipe 115 also leads from the upper part of the cylinder 87 to the receptacle 92 to provide for the return of any liquid that leaks past the piston 86.

In the operation of the pump, it will be understood that as soon as the nozzle is removed from the hook and its valve opened, the pressure in the system is immediately relieved, permitting the piston 86 and dog 78 to drop, closing the circuit through the motor. The operation of the pump then begins and a measured gallon is discharged for each complete cycle of its operation. While the pump is delivering the last gallon, the nozzle valve is partially closed and this sets up sufficient pressure in the system to raise the dog 78 into position to positively stop precisely at the completion of its cycle. Thus the flow of liquid can be started and stopped at a positively fixed point unaffected by momentum or friction. The measure of the liquid by displacement cannot be affected in any way by variation in the density of the liquid or its temperature or by change of speed or other causes. The stopping of the pump does not depend at all upon the dexterity of the operator.

In case the inlet to the receptacle to be filled cannot take the full capacity of the pump and it becomes necessary to partially close the nozzle valve, the operation of the pump will be temporarily checked as the delivery of each gallon is completed, but will immediately resume its operation as the pressure is relieved through the open nozzle.

The indicator will ordinarily be reset at zero after each sale. If a fraction of a gallon is dispensed, the remainder of the gallon should be discharged from the pump before it is reset.

In case the pump remains idle for a considerable time so that the pressure in the system is lowered sufficiently to permit the dog 78 to drop below stopping position, the pressure can immediately be restored through the operation of the hand lever 99. There is absolutely no waste of liquid, since all leakage is drained into the receptacle 92. All of the parts of the system may be easily assembled and are readily taken apart for inspection.

While we have shown and described in considerable detail the preferred construction of the invention, it will be understood that the

same may be considerably modified without any material departure from the essential features of the invention, as defined in the claims.

What we claim is:

1. A dispensing pump including a cylinder, a piston cooperating therewith, mechanism for reciprocating said piston, a discharge pipe and nozzle connected with said cylinder, an abutment on said mechanism, a stop member shiftable into the path of said abutment to stop said mechanism, and means operable by pressure created by said piston, when the nozzle outlet is restricted, to shift said stop member to stopping position. 89

2. A dispensing pump including a cylinder, a piston in said cylinder, mechanism including a rotary member for reciprocating said piston, an abutment carried by said rotary member, a dog shiftable in the path of said abutment, and a piston operable, by pressure developed by the first mentioned piston when the outlet is restricted, to shift said dog and thereby positively stop the pump at the completion of a predetermined cycle. 90

3. A dispensing pump including a cylinder, a piston cooperating therewith, mechanism for reciprocating said piston, means including an electric motor for driving said mechanism, a discharge pipe and nozzle connected with said cylinder, means operable by pressure created by said piston, when the nozzle outlet is restricted, for positively stopping said pump at the completion of a predetermined cycle, means for automatically interrupting the circuit through the motor as the cycle is completed, and means for again closing the circuit through the motor as soon as the pressure in the system is relieved. 95

4. A dispensing pump including a cylinder, a piston cooperating therewith, mechanism for reciprocating said piston, means including an electric motor for driving said mechanism, a discharge pipe and nozzle connected with said cylinder, an abutment on said mechanism, a stop member shiftable into the path of said abutment to stop said mechanism, and means operable by pressure created by said piston, when the nozzle outlet is restricted, to shift said stop member to stopping position, means associated with said stop member for automatically interrupting the circuit through the motor at the completion of a predetermined cycle, and means for again closing a circuit through the motor as soon as the pressure in the system is relieved. 100

5. A dispensing pump including a cylinder, a piston cooperating therewith, a rotary member for reciprocating said piston, means including an electric motor for driving said rotary member, an abutment carried by said rotary member, a dog shiftable into the path of said abutment, a piston operable, by pressure developed by the first mentioned piston when the outlet is restricted, to shift said 125

5 dog and thereby positively stop the pump at the completion of a predetermined cycle, means automatically actuated by said abutment to interrupt the circuit through the motor as the cycle is completed, and means for again closing the circuit through the motor as soon as the pressure in the system is relieved.

10 6. A dispensing pump including a cylinder, a piston cooperating therewith, mechanism for reciprocating said piston, a discharge pipe and nozzle connected with said cylinder, means operable by pressure created by said piston, when the nozzle outlet is restricted, for positively stopping said mechanism at the completion of a predetermined cycle, and manually operable means for restoring said pressure in case it becomes reduced by leakage.

15 7. A dispensing pump including a cylinder, a piston cooperating therewith, mechanism for reciprocating said piston, a discharge pipe and nozzle connected with said cylinder, an abutment on said mechanism, a stop member shiftable into the path of said abutment to stop said mechanism, means operable by pressure created by said piston, when the nozzle outlet is restricted, to shift said stop member to stopping position, and manually operable means to restore said pressure in case it becomes reduced by leakage.

20 8. A dispensing pump including a cylinder, a piston in said cylinder, mechanism including a rotary member for reciprocating said piston, an abutment carried by said rotary member, a dog shiftable in the path of said abutment, a piston operable, by pressure developed by the first mentioned piston when the outlet is restricted, to shift said dog and thereby positively stop the pump at the completion of a predetermined cycle, and manually operable means to restore said pressure in case it becomes reduced by leakage.

25 9. A dispensing pump comprising two double acting pump units, each including a cylinder and a reciprocating piston, a common discharge conduit and nozzle for said pump units, mechanism for actuating said pistons with one piston half a stroke in advance of the other, and means operable by pressure created in the conduit when the nozzle outlet is restricted, for positively stopping said mechanism at the completion of a predetermined cycle.

30 10. A dispensing pump including a cylinder, a piston cooperating therewith, mechanism for reciprocating said piston, a discharge pipe and nozzle connected with said cylinder, means operable by pressure within said pipe to positively stop said mechanism at the completion of a predetermined cycle, a receptacle, means for draining into said receptacle any leakage which takes place from the pump, and means for utilizing liquid from

said receptacle to restore the pressure when it is reduced by leakage.

11. A dispensing pump including a cylinder, a piston cooperating therewith, mechanism for reciprocating said piston, a discharge pipe and nozzle connected with said cylinder, an abutment on said mechanism, a stop member shiftable into the path of said abutment to stop said mechanism, means operable by pressure created by said piston, when the nozzle outlet is restricted, to shift said stop member to stopping position, a receptacle, means for draining into said receptacle any leakage from the pump, and means for utilizing liquid from said receptacle to restore the pressure when it is reduced by leakage.

15 12. A dispensing pump including a cylinder, a piston in said cylinder, mechanism including a rotary member for reciprocating said piston, an abutment carried by said rotary member, a dog shiftable in the path of said abutment, a piston operable, by pressure developed by the first mentioned piston when the outlet is restricted, to shift said dog and thereby positively stop the pump at the completion of a predetermined cycle, a receptacle, means for draining into said receptacle any liquid which leaks out around the piston rod, and means for utilizing liquid from said receptacle to restore the pressure when it is reduced by leakage.

20 13. A dispensing pump including a cylinder, a piston cooperating therewith, mechanism for reciprocating said piston, means including an electric motor for driving said mechanism, a discharge pipe and nozzle connected with said cylinder, means operable by pressure created by said piston, when the nozzle outlet is restricted, for positively stopping said pump at the completion of a predetermined cycle, means for automatically interrupting the circuit through the motor as the cycle is completed, means for again closing the circuit through the motor as soon as the pressure in the system is relieved, a packing gland for the piston rod, a receptacle, means for draining into said receptacle any leakage which takes place through said gland, and means for utilizing liquid from said receptacle to restore the pressure when it is reduced by leakage.

25 14. A dispensing pump including a cylinder, a piston cooperating therewith, mechanism for reciprocating said piston, means including an electric motor for driving said mechanism, a discharge pipe and nozzle connected with said cylinder, an abutment on said mechanism, a stop member shiftable into the path of said abutment to stop said mechanism, means operable by pressure created by said piston, when the nozzle outlet is restricted, to shift said stop member to stopping position, means associated with said stop member for automatically interrupting the circuit

through the motor at the completion of a pre-determined cycle, means for again closing a circuit through the motor as soon as the pressure in the system is relieved, a receptacle, 5 means for draining into said receptacle any liquid which leaks out around the piston rod, and manually operable means for injecting liquid from said receptacle into the discharge pipe to restore pressure therein when it is 10 reduced by leakage.

15. A dispensing pump including a cylinder, a piston cooperating therewith, a rotary member for reciprocating said piston, means including an electric motor for driving said rotary member, an abutment carried by said rotary member, a dog shiftable into the path of said abutment, a piston operable, by pressure developed by the first mentioned piston when the outlet is restricted, to shift said dog 20 and thereby positively stop the pump at the completion of a predetermined cycle, means automatically actuated by said abutment to interrupt the circuit through the motor as the cycle is completed, means for again closing 25 the circuit through the motor as soon as the pressure in the system is relieved, a packing gland about said piston, a receptacle, means for draining into said receptacle any liquid that may leak out through said gland, 30 and means for restoring said liquid to the system to increase the pressure when it has been reduced by leakage.

In testimony whereof we have hereunto signed our names to this specification.
